UNITED STATES PATENT OFFICE.

CHARLES H. NOWACK, OF CHICAGO, ILLINOIS, ASSIGNOR TO AMERICAN CAN COMPANY, OF NEW YORK, N. Y., A CORPORATION OF NEW JERSEY.

HINGE-COVER BOX.

1,385,575.

Specification of Letters Patent. Patented July 26, 1921.

Application filed March 29, 1917. Serial No. 158,155.

To all whom it may concern:

Be it known that I, CHARLES H. NOWACK, a subject of the Emperor of Austria-Hungary, residing in Chicago, in the county of 5 Cook and State of Illinois, have invented a new and useful Improvement in Hinge-Cover Boxes, of which the following is a specification.

This invention relates in general to hinge 10 cover boxes and has more particular reference to cracker boxes and the like.

A principal object of this invention is the provision of a hinge for a box or container for packaging crackers or other material, 15 which will permit of the permanent securing of the part of the hinge connection to the body of the box without the use of solder and after the box is completely formed.

A further object of the invention is the 20 provision of a hinge connection of unusual strength, of durability equal to the durability of the remainder of the box construction, and which will not require expensive machinery to construct or assemble.

25 A further object of the invention is the provision of such a hinge which will not mar the outside appearance of the box.

Other objects and advantages of the invention will be apparent as it is better understood from the following description when considered in connection with the accompanying drawing illustrating a preferred embodiment thereof.

On the drawing,

35 Figure 1 is a perspective view of a box embodying my invention;

Fig. 2 is a transverse vertical section of the same;

Fig. 3 is an enlarged section taken substantially on the line 3—3 of Fig. 2; and

40 Fig. 4 is an enlarged perspective view of the strip for forming the part of a hinge connection, which is secured to the body.

For the purpose of illustrating my invention I have shown on the drawing a cracker box of well known type and appearance and which will not need particular detailed description. It may, however, be mentioned that the box is constructed in 45 the present instance of metallic sheet material, the upper edges 11 of the walls 12 being bent about and embracing a suitable reinforcing 13. The cover indicated at 14 is of usual type adapted to close down over the body and embraces at its lower edge a wire

or rod 15 which is continuous about the embracing flange 16 which closes down over the body. The embracing flange 16 is cut away at two points at the rear to expose the wire or rod and permit the location of hinge connections to pivotally secure the cover to the body. Since the two hinge connections between the cover and box or body are duplicates of each other in the present instance, a description of one of them will be 60 sufficient for the two.

A strip of metal embraces the rod or wire 18' at one of the exposed locations mentioned and this strip is provided with a central loop 17 through the aperture 18 of 70 which the wire or rod is placed. The strip is bent completely around this rod or wire into substantial contact at 19 and outwardly from the loop a substantial distance is bent back upon itself at 20, the length of the 75 strip being such that the extreme ends 21 are thus brought past the central part of the strip which embraces the wire. Just inwardly of this part they are bent out at 22. The loops 20 are inserted through a suitably 80 positioned aperture 23 in the rear of the box body and are then separated and bent at the points 34 into parallelism with the bent extreme ends 21 so that each of these extreme ends and its companion loop forms 85 a channel into which the material above and below the aperture engages. The member of the hinge connection which is fixed to the body is thus locked in place through the interlocking engagement of the strip and box 90 body. The connection thus formed is of considerable strength since the material of the body is clamped individually at each end of the hinged strip reinforcing the material about the aperture through engagement with the side walls.

It is thought that the invention and many of its attendant advantages will be understood from the foregoing description, and it will be apparent that various changes may 100 be made in the form, construction and arrangement of the parts without departing from the spirit and scope of the invention or sacrificing any of its material advantages, the form hereinbefore described being 105 merely a preferred embodiment thereof.

I claim:

1. A box constructed of sheet material, a cover therefor, and a hinge connection between said cover and box, a part of said 110

- connection fixed to the box comprising a strip of material pivotally connected to the cover and having its ends extending through an aperture into said box, said strip being formed into loops, both loops extending into the inside of the box, and the ends of said loops extending back to the outside of the box. 35
- 5 bent to provide shoulders of two thicknesses of said strip engaging the inner faces of said box at said aperture. 5. A box, a cover therefor, and a hinge connection between said cover and said box, said connection comprising a pintle carried by the cover, and a strip of material 40
bracing the pintle and having its ends formed into loops, both loops extending into the inside of the box and the ends of the loops being disposed without the box, said loops and ends being bent into parallelism 45 to lock the strip in place.
2. A box, a cover therefor, and a hinge connection between said cover and said box, 10 a part of said connection fixed with respect to the box comprising a strip of metal formed with a loop pivotally connected to the cover and having its ends disposed through an aperture in the box and each end 15 bent to lock the body of the box at the aperture with said end, said ends being held between the box and said loop. 6. A box, a cover therefor, and a hinge connection between said cover and said box, said connection comprising a pintle carried by the cover, and a strip of sheet material 50
embracing the pintle, the ends of said strip being formed into oppositely extending channels the inner walls of which consist of two thicknesses of said strip, the folded strip being disposed through an aperture in the 55 box with the material about the aperture resting in said channels.
3. A box, a cover therefor, and a hinge connection between said cover and said box, 20 said connection comprising a pintle carried by the cover, and a strip of sheet material embracing said pintle and extending into the box, said strip being folded to form two thicknesses of said material and so as to 25 cause its outer and inner portions to engage both the outside and inside of the box respectively to secure the strip to the box.
4. A box, a cover therefor, and a hinge connection between said cover and said box, 30 said connection comprising a pintle carried by the cover, and a strip of material embracing the pintle and having its ends

Signed in the presence of two subscribing witnesses.

CHARLES H. NOWACK.
